US00D944656S

(12) **United States Design Patent** (10) **Patent No.:** **US D944,656 S**
(45) **Date of Patent:** **** Mar. 1, 2022**

(54) **CARRIER**

(71) Applicant: **Graphic Packaging International, LLC**, Atlanta, GA (US)

(72) Inventor: **Raymond R. Spivey, Sr.**, Mableton, GA (US)

(73) Assignee: **Graphic Packaging International, LLC**, Atlanta, GA (US)

(**) Term: **15 Years**

(21) Appl. No.: **29/740,756**

(22) Filed: **Jul. 7, 2020**

(51) LOC (13) Cl. **09-03**

(52) U.S. Cl.

USPC **D9/753; D9/752**

(57) **CLAIM**

The ornamental design for a carrier, as shown and described.

DESCRIPTION

The disclosures of each of U.S. Provisional Patent Application No. 62/779,689, filed on Dec. 14, 2018, U.S. Provisional Patent Application No. 62/783,752, filed on Dec. 21, 2018, U.S. Provisional Patent Application No. 62/796,830, filed on Jan. 25, 2019, U.S. Provisional Patent Application No. 62/797,585, filed on Jan. 28, 2019, U.S. Provisional Patent Application No. 62/810,015, filed on Feb. 25, 2019, U.S. Provisional Patent Application No. 62/814,412, filed on Mar. 6, 2019, U.S. Provisional Patent Application No. 62/817,120, filed on Mar. 12, 2019, U.S. Provisional Patent Application No. 62/841,449, filed on May 1, 2019, U.S. patent application Ser. No. 16/426,050, filed on May 30, 2019, U.S. patent application Ser. No. 16/426,057, filed on May 30, 2019, U.S. patent application Ser. No. 16/426,060, filed on May 30, 2019, U.S. patent application Ser. No. 16/426,063, filed on May 30, 2019, U.S. patent application Ser. No. 16/426,066, filed on May 30, 2019, U.S. Design patent application Ser. No. 29/692,992, filed on May 30, 2019, U.S. Design patent application Ser. No. 29/692,993, filed on May 30, 2019, U.S. Design patent application Ser. No. 29/692,994, filed on May 30, 2019, U.S. Design patent application Ser. No. 29/692,996, filed on May 30, 2019, U.S. Design patent application Ser. No. 29/692,997, filed on May 30, 2019, U.S. patent application Ser. No. 16/598,282, filed on Oct. 10, 2019, U.S. Design patent application Ser. No. 29/709,918, filed on Oct. 18, 2019, U.S. Provisional Patent Application No. 62/952,839, filed on Dec. 23, 2019, U.S. Provisional Patent Application No. 62/956,882, filed on Jan. 3, 2020, U.S. Provisional Patent Application No. 62/985,997, filed on Mar. 6, 2020, U.S. patent application Ser. No. 16/829,346, filed on Mar. 25, 2020, U.S. Provisional Patent Application No. 63/015,898, filed on Apr. 27, 2020, U.S. Provisional Patent Application No. 63/022,757, filed on May 11, 2020, and U.S. Provisional Patent Application No. 63/023,442, filed on May 12, 2020, U.S. Design patent application Ser. No. 29/735,178, filed on May 19, 2020, U.S. Provisional Patent Application No. 63/031,615, filed on May 29, 2020, U.S. Design patent application Ser. No. 29/739,927, filed on Jun. 30, 2020, U.S. Design patent application

(Continued)

Ser. No. 29/739,929, filed on Jun. 30, 2020, U.S. Design patent application Ser. No. 29/739,931, filed on Jun. 30, 2020, U.S. Design patent application Ser. No. 29/739,933, filed on Jun. 30, 2020, and U.S. Design patent application Ser. No. 29/739,934, filed on Jun. 30, 2020, are hereby incorporated by reference for all purposes as if presented herein in their entirety.

FIG. 1 is a perspective view of a carrier showing our new design.

FIG. 2 is a front elevation view of the carrier of FIG. 1, the rear elevation view is a mirror image.

FIG. 3 is a left elevation view of the carrier of FIG. 1, the right elevation view is a mirror image.

FIG. 4 is a top plan view of the carrier of FIG. 1.

FIG. 5 is a bottom plan view of the carrier of FIG. 1; and, FIG. 6 is a plan view of the carrier of FIG. 1 shown in an unfolded configuration.

All evenly-spaced broken lines are for environmental purposes only and do not form part of the claimed design.

1 Claim, 6 Drawing Sheets
